ELECTRIC CORD TAKE-UP

Filed June 16, 1926

Witness:

Bred L. Fischer.

By

F. G. Fischer,
Attorney.

UNITED STATES PATENT OFFICE.

THOMAS M. BURNS, OF KANSAS CITY, MISSOURI.

ELECTRIC-CORD TAKE-UP.

Application filed June 16, 1926. Serial No. 116,415.

My invention relates to a device for taking up the slack in the electric cord of an electric iron while the latter is in use, so that said cord cannot become twisted, or entangled 5 with articles being ironed.

While the invention is herein shown and described in connection with an electric iron, it is to be understood that it may be used with other electrical devices.

10 In order that the invention may be fully understood, reference will now be had to the accompanying drawing, in which:

Fig. 1 is a side elevation showing the device applied to an ironing board.

15 Fig. 2 is a fragmentary front elevation of a portion of the device.

Fig. 3 is a vertical section on line 3—3 of Fig. 2.

20 Fig. 4 is a horizontal section on line 4—4 of Fig. 3.

Fig. 5 is a horizontal section on line 5—5 of Fig. 3.

25 Fig. 6 is a fragmentary rear elevation of a portion of an arm forming part of the invention.

Fig. 7 is a vertical section on line 7 of Fig. 6.

Referring in detail to the different parts, A 30 designates an ironing board, B an electric iron, and C an electric cord or conductor with which said iron B is equipped.

Referring now more particularly to the device constituting the invention, 2 designates a bracket adapted to fit over the edge of the ironing board A and provided with a thumb screw 4 whereby it may be firmly secured in place. The bracket 2 is equipped with an electric switch D for controlling the flow of current through the cord C from a source of electrical energy, not shown, to the iron B.

40 The upper end of the bracket 2 terminates in a cylindrical stud 6 upon which a member 8 is swiveled. The member 8 is held in place by suitable means consisting preferably of a cotter pin 10 which extends laterally through said member 8 and an annular groove 12 in the upper portion of the stud 6, Fig. 3.

14 designates a fitting mounted upon a pivot 16 preferably in the form of a cotter pin, and extending through the bifurcated 50 upper portion of the member 8. The main body of the fitting 14 extends downwardly at the rear portion of the member 8 and is thereby prevented from moving backwardly upon

the pivot 16 beyond a vertical position, but is free to rock forwardly when in use, as 55 shown by Fig. 1.

Rocking of the fitting 14 is yieldably resisted by a spring 18 coiled loosely around the pivot 16 and having its lower end bearing against the member 8 and its upper end engaged with a notched segment 20 fixed to the forward upper portion of said member 8. The tension of the spring 18 may be regulated as desired by engaging its upper end in different notches of the segment 20. A bifurcated lug 22 projects rearwardly from the upper portion of the fitting 14 and is provided with a rubber or other suitable bushing 24 through which the cord C extends from the switch D.

26 designates a resilient arm consisting of a suitable number of sections 28 foldably connected by pivots 30. The lowermost section of the arm 26 is secured to the rear side of the fitting 14 by a pivot 32, which is preferably 70 in the form of a screw as shown by Fig. 3. When the arm 26 is extended as shown by Fig. 1, its lower section 28 is prevented from accidentally folding by fitting within a recess 34 in the lug 22 and also by a detent 36 projecting from the rear portion of the fitting 14 to enter a corresponding opening in the section 28. The intermediate and top sections 28 are prevented from accidentally folding when in use by detents 38 spaced at opposite 80 sides of the pivots 30. The upper section 28 of the arm 26 has a rubber or other suitable bushing 40, which cooperates with the bushing 24 in firmly securing the electric cord C to the device.

With the parts constructed and arranged as shown and described it is apparent that as the iron B is moved forward and backward over the ironing board A that the electric cord C will at all times be held out of the way by 90 the arm 26, which latter, however, is free to yield sufficiently to allow the iron B to be moved to the other end of the board from that to which the device is attached.

When the device is not in use the sections 100 28 of the arm 26 may be folded upon each other and down against the bracket 2, so that the device may be stored in a small space.

While I have shown and described the preferred construction, combination and arrangement of parts, I reserve the right to all 105

such changes and modifications as properly fall within the spirit and scope of the invention as claimed.

Having thus described my invention, what I claim and desire to secure by Letters Patent, is:

1. In a take-up device for the cords of electric irons, a lower arm section, a support adapted to be clamped to an ironing board 10 and upon which said section is rockably mounted at its lower end, an intermediate arm section pivotally connected at its lower end to the upper end of the first-mentioned section, an upper arm section pivotally connected at its lower end to the upper end of said intermediate section, and an insulating bushing secured to the upper section and through which the cord of the iron extends.

2. A take-up device for the cords of electric irons consisting of adjustable clamping means for engaging over the edge of an iron-

ing board, a stud extending upwardly from said clamping means, a member swiveled upon said stud, a segment rockably mounted upon the member and having notches in its upper curved portion and a downward extension for contacting with said member to limit the rocking movement of the segment, a spring engaging the member and the notched portion of said segment for yieldably holding the latter in upright position and against said member, an arm pivotally connected to said segment and provided at its upper end with a tubular support through which the cord of the iron extends, a bifurcated lug projecting from the segment and provided with a recess to receive the adjacent edge of said arm, and a tubular support carried by said lug and through which the cord extends.

In testimony whereof I affix my signature.

THOMAS M. BURNS.
